BURNISHING BRUSH CONTROL FOR SHOE
POLISHING MACHINES

John J. Magnuson, Waynesboro, Pa., assignor to
The Magnus Automatic Machine Company, In-
corporated, Waynesboro, Pa., a corporation of
Delaware

Application June 16, 1936, Serial No. 85,562

4 Claims. (Cl. 15—35)

This invention relates to shoe polishing machines, and more particularly to that type of shoe polishing machine shown in my copending application Serial Number 82,100, filed May 27, 1936, for Shoe polishing machine, wherein a polishing and polish-applying brush has a planetary movement about a foot-rest.

In this type of shoe polishing machine the extra polishing brush necessary for the tip of the shoe, and more particularly the upper part thereof, must necessarily have an oscillatory movement in order that it may clear the planetary brush as it moves about the shoe.

Considerable difficulty is met with in securing a proper burnish for the shoe tip, as the brush in its oscillatory movement has a tendency to skip the edge portions or sides of the shoe and leave the same insufficiently burnished. Furthermore, with the ordinary construction the oscillation is necessarily more or less rapid, further decreasing the chances of proper burnishing.

An important object of this invention is the provision of an arrangement whereby the tip burnishing brush may be moved across the tip of the shoe very slowly and be caused to dwell at that side of the shoe at which the bristles or fiber of the brush tend to separate from the shoe due to the direction of rotation of the brush, and more specifically the provision of an arrangement whereby the return movement of the brush can be made extremely rapid thereby enabling the greatest possible polishing time to be utilized.

Another object of the invention is the provision of a structure of this character in which the parts may be arranged within the smallest possible compass and at the same time be durably constructed so that they may operate efficiently through a considerable period without continual attention.

These and other objects I attain by the construction shown in the accompanying drawings wherein, for the purpose of illustration, I have shown a preferred embodiment of my invention and wherein:

Fig. 1 is a perspective view of the interior mechanism of a shoe polishing machine constructed in accordance with my invention;

Fig. 2 is a sectional view on line 2—2 of Fig. 3;

Fig. 3 is a section on line 3—3 of Fig. 2; and

Fig. 4 is a section on line 4—4 of Fig. 2.

Referring now more particularly to the drawings, the numeral 10 generally designates an inclined platform from which perpendicularly extends a standard 11. This standard is surrounded by a rotatable unit 12 in substantially all

respects identical with that described in the co-pending application above referred to and has at its upper end a foot-rest 13. The rotatable unit includes an oscillatable arm 14 bearing the brush shaft 15 having a polishing and polish-applying planetary brush 16 secured thereto. The shaft of this brush is guided through a slot 17 formed in a disc 18 likewise forming a part of the rotating unit for in-and-out movement to enable it to accommodate itself to the contour 10 of the foot-rest and this in-and-out movement is supplied by a cam 19 attached to the foot-rest. The brush-bearing arm 14 is constantly urged inwardly by a spring 19a connecting this arm with the hub of the unit 12 surrounding the standard 11. Polish is supplied to the brush 16 through a distributing shield 20 such as described in said copending application and the distribution of polish to this shield from the polish container 21 is obtained through an intermittently 20 operating measuring force pump 22 actuated by a gear cam unit 23 driven from the unit 12, said force pump being supplied by a circulating pump 24. These elements are all substantially as described in the said copending application and 25 form no part of my invention except in the combination as hereinafter set forth.

The rotatable unit is driven through a motor-driven belt 25 and a worm shaft 26 cooperating with a worm gear 27 forming a portion of the 30 unit, such belt 25 likewise driving a shaft 28 mounted in bearings 29 carried by the rear end of the inclined platform 10. Aligned with shaft 28 and mounted in bearings 30 for oscillation is an oscillatory shaft 31, said shaft 31 having secured thereto a yoke 32 mounting a stub shaft 33. Oscillatable about the stub shaft is a standard 34 the upper end of which rotatably mounts a brush shaft 35 having the toe burnishing brush 36 secured thereto. Rotatable upon the stub shaft 40 33 is a combined friction disc and pulley 37 the pulley element of which is connected with a pulley 38 on brush shaft 35 by a belt 39. Shaft 28 has a spring-pressed friction disc 40 for co-action with the friction disc of element 37. Likewise 45 mounted upon and secured to the oscillatory shaft 31 is a unit comprising arms 41 and 42, the arm 41 being connected to the platform by the spring 43 and the arm 42 having an adjustable stop 44 directed therethrough for engagement with the platform so that oscillation of shaft 31 under action of spring 43 may be adjustably limited.

Slidable upon the oscillatory shaft 31 is a collar 45 engaged by a fork 46 pivoted at 47 to the plat- 55

form and having its opposite end co-acting with a cam 48 secured to the under surface of the gear 27, a spring 49 maintaining engagement of the cam and shifting fork. This collar has pivoted thereto one end of a link 50, the opposite end of which is pivoted to the standard 34 and it will be obvious that as gear 27 is rotated the cam 48 will cause the standard to oscillate to and fro in the direction of the arrow A of Figure 2. Yoke 32 has an arm 51 pivoted to one end of a thrust bar 52 the opposite end of which is forked straddling the rotatable unit 12 above the gear 27 and having a roller 53 co-acting with a cam 54 secured to the unit. This cam will obviously cause longitudinal reciprocation of the thrust arm 52 and, accordingly, oscillation of the standard 34 about the shaft 31 as a pivot and in the general direction of the arrow B of Figure 1. Cams 48 and 54 having the proper conformation and being properly disposed as regards the unit 12, it will be obvious that the brush standard may be oscillated to elevate brush 36 out of the path of movement of the brush 16 and since this elevation can be rapidly effected, it can be delayed until the last possible moment. This enables the burnishing brush to dwell in its engagement with the shoe tip at the far side of the shoe or at the limit of its movement so that a proper burnishing of this portion of the shoe may be obtained. The cam 54 will, of course, suddenly release the standards, enabling the same to be returned immediately to its polishing level by the spring 43. Cam 48 will serve to control the speed of movement of the burnishing brush across the tip of the shoe and since the engagement with the shoe is determined by the spring 43 the pressure applied by the brush may be very closely regulated at all times.

The drive employed for the planetary brush is substantially a duplicate of that illustrated in the application above identified. It comprises a friction disc 55 co-acting with friction disc 56 upon shaft 26 and having a pulley 57 driving a compound pulley unit 58 rotatably mounted upon the unit 12. Suitable belting connects this pulley unit with the shaft of the planetary brush.

Since the construction illustrated is obviously capable of considerable modification without materially departing from the spirit of my invention, I do not wish to be understood as limiting myself thereto except as hereinafter claimed.

I claim:

1. In a shoe polishing machine, a foot-rest, a standard, a rotatable toe burnishing brush carried by the standard, means to rotate the toe burnishing brush, means to oscillate the standard toward and away from the toe part of the foot-rest in a direction longitudinal thereto to thereby move the brush into and out of operative

engagement with a shoe on said foot-rest, and means to oscillate the standard transversely of the foot-rest to thereby move the brush across the toe part of the foot-rest.

2. In a shoe polishing machine, a foot-rest, a member mounted for oscillation, a standard pivoted to said member for oscillation about an axis perpendicularly related to the axis of oscillation of the member, a rotatable toe burnishing brush carried by the standard, means to rotate said brush, means to oscillate said member in a direction longitudinal to the foot-rest to cause the brush to move toward and away from the toe part of the foot-rest and into and out of operative engagement with a shoe on said foot-rest, and means to oscillate said standard upon the member in a direction transverse to the foot-rest to cause the brush to move across the toe part of a shoe on the foot-rest.

3. In a shoe polishing machine, a foot-rest, a member mounted for oscillation, a standard pivoted to said member for oscillation about an axis perpendicularly related to the axis of oscillation of the member, a rotatable toe burnishing brush carried by the standard, means to rotate said brush, means to oscillate said member in a direction longitudinal to the foot-rest to cause the brush to move toward and away from the toe part of the foot-rest and into and out of operative engagement with a shoe on said foot-rest, means to oscillate said standard upon the member in a direction transverse to the foot-rest to cause the brush to move across the toe part of a shoe on the foot-rest, and means correlating the oscillations of said member and standard constructed and arranged to insure movement of the brush across the toe part when in operative position in one and the same direction.

4. In a shoe polishing machine, a foot-rest, a polishing and polish-applying brush, means to rotate said brush and cause the same to circumambulate the foot-rest, a standard, a toe burnishing brush carried by the standard, means to rotate the toe burnishing brush, means to oscillate the standard toward and away from the toe part of the foot-rest in a direction longitudinal to the foot-rest whereby to move the brush into and out of operative engagement with a shoe on the foot-rest, means to oscillate the standard transversely of the foot-rest to cause the brush to travel across the toe part of the foot-rest, said oscillating means operating in timed relation with the movement of the first-named brush about the toe part to cause operative engagement between the toe burnishing brush and the shoe on the foot-rest when the first-named brush is removed from the toe part of the foot-rest.

JOHN J. MAGNUSON.
